DESIGN FOR A PORTABLE ELECTRIC LANTERN

Carl A. Glock, Lynwood, Calif.

Application October 5, 1935, Serial No. 58,841

Term of patent 3½ years

To all whom it may concern:

Be it known that I, Carl A. Glock, a citizen of the United States, residing at Lynwood, in the county of Los Angeles and State of California, have invented a new, original, and ornamental Design for a Portable Electric Lantern, of which the following is a specification, reference being had to the accompanying drawing, forming a part thereof.

The figure is a side elevational view of a portable electric lantern showing my new design.

The design is circular in horizontal cross section, and the appearance of the opposite side is identical with the side shown in the drawing.

I claim:

The ornamental design for a portable electric lantern, as shown and described.

CARL A. GLOCK.
